FUSE SWITCH

John L. Turner, East St. Louis, Ill., assignor to
 W. N. Matthews Corporation, St. Louis, Mo., a
 corporation of Missouri

Application May 4, 1950, Serial No. 159,968

6 Claims. (Cl. 200—117)

1

This invention relates to fuse switches and more particularly to such switches wherein a fuse link is held under tension and which are adapted for out-door service on electrical power line poles or the like.

The object of the invention is the provision of an improved fuse switch of the class described which is of economical construction and which operates reliably to separate the terminals of a fuse link upon blowing of the link, even under severe icing conditions.

In general, a fuse switch of this invention comprises an insulator or insulators such as may be mounted vertically or in angle underhung position on a cross arm on a power line pole. A terminal adapted for attachment of one lead of a conventional fuse link is mounted on the insulator. Also mounted on the insulator is an electrically conductive resilient rod having a portion coiled about an axis into a helically convoluted spring, the convolutions of which are axially displaced, and another portion thereof forming a cantilever arm extending outward from one end of the spring generally transverse to the direction of length of the spring. The spring has its other end secured to the insulator spaced from the terminal with the arm extending outward away from the insulator. The arm is adapted for attachment of the other lead of the fuse link to its free end when its free end is forced against the bias of the spring toward the terminal, so as to hold the fuse link under tension between the terminal and the free end of the arm. The spring is secured to the insulator in such position that when the free end of the arm is forced toward the terminal, the convolutions of the spring are forced together on one side of the spring axis and forced apart on the other. Other features will be in part apparent and in part pointed out hereinafter.

The invention accordingly comprises the elements and combinations of elements, features of construction, and arrangements of parts which will be exemplified in the structures hereinafter described, and the scope of the application of which will be indicated in the following claims.

In the accompanying drawing, in which one of various possible embodiments of the invention is illustrated,

Fig. 1 is a view in elevation of a fuse switch of this invention as it is mounted on a cross-arm holding a fuse link under tension;

Fig. 2 is a plan view of Fig. 1 as viewed on the line 2—2 of Fig. 1;

2

Fig. 3 is a fragmentary detail as viewed on the line 3—3 of Fig. 1; and

Fig. 4 is a section taken on line 4—4 of Fig. 1.

Similar reference characters indicate correspondingly parts through the several views of the drawing.

Referring to the drawing, a fuse switch of this invention is shown to comprise an elongate insulator 1 which is equipped with a bracket 3 for mounting the insulator in angle underhung position on a cross-arm on a power line pole, or which can be furnished with a bracket for mounting in vertical position. At the upper end of the insulator is a terminal 5 for attachment of one lead of a fuse link 7. An electrically conductive spring terminal 9 extends outward from the lower end of the insulator and is adapted to be flexed against its inherent bias toward the terminal 5 for attachment of the other lead of the fuse link 7 to its free end for holding the fuse link under tension. The invention resides particularly in the construction of the spring terminal 9 and its attachment to the end of the insulator.

The terminal 5 comprises a length of electrically conductive resilient rod (a copper alloy rod, for example) bent to form a loop 11 shaped like an inverted U with arms 13 extending at right angles to the plane of the loop from the lower ends of the legs of the loop. These arms are bent toward one another to meet at 15 and have straight portions 17 engaged side-by-side extending to the free end of the terminal 5 where the arms have portions 19 bent back and flared outward to provide two clip portions 20 in either of which may be wedged the flexible lead 21 extending from one end of a fuse link tube 23. The outer ends of the arm portions 17 are held together by a cap 25. On one leg of the loop is a conventional bolt connector 27 for attaching a conductor (not shown) to the terminal. The terminal is clamped to the upper end of the insulator by means of a clamp member 29 bolted to the insulator as indicated at 31 with the legs of the loop 11 held in the clamp, with the loop extending upward above the upper end of the insulator, and with the arms 13 extending transversely outward from the insulator.

The spring terminal 9 is made of a length of electrically conductive resilient rod (copper alloy rod, for example) having a portion thereof coiled about an axis into a helically convoluted spring 33, the convolutions of which are axially displaced, (i. e., the spring is not a flat spiral spring) and another portion thereof forming a cantilever

arm extending outward from one end of the spring in a direction generally transverse to the direction of the length of the spring and in a plane including, or at least approximately including, the axis of the spring. For example, when the spring is unstressed, the arm may extend approximately at right angles to the spring axis. A portion of the rod is formed into a loop 37 extending outward from the other end of the spring generally parallel to and spaced from the spring axis.

The arm 35 has a portion 39 at its free end bent back and flared outward to provide a clip 41 in which may be wedged the flexible lead 43 extending from the other end of the fuse link tube 23. A cap 45 is fitted on the doubled end of the arm. The arm may be bent as indicated at 47 to provide a wide throat 49 for facilitating entry of the lead 43 in the clip 41. The loop 37 is of U shape. A generally straight reach 51 of the rod extending at right angles to the plane of the loop from the end of one of its legs leads into the end of the spring. An end reach 53 of the rod extends from the end of the other leg of the loop alongside the reach 51.

An angle bracket 55 has one leg 57 bolted to the lower end of the insulator as indicated at 59 with its other leg 61 extending generally transversely outward from the lower end of the insulator on the same side of the insulator as the terminal 5. The spring 33 is secured at its looped end to the leg 61 of the bracket with its axis positioned at least approximately in the vertical plane including the terminal 5 and with the arm 35 extending outward away from the insulator at least approximately in this plane. As shown, the spring is secured to the leg 61 with its axis generally parallel to the axis of the insulator and with the arm 35 extending outward from the upper end of the spring, the reaches 51 and 53 being clamped against the bottom of the leg 61 by means of a clamping member 63 bolted to the leg 61 as indicated at 65. On one leg of the loop 37 is a conventional bolt connector 67 for attaching a conductor (not shown) to the loop 37.

On the ends of the fuse link leads 21 and 43 are heads 71 and 73 and rings 75 and 77, respectively. The fuse link is applied by raising the link with a hook stick, the hook being inserted in ring 75, wedging the lead 43 in clip 41, lifting the link after the lead 43 is wedged in the clip to force the free end of the arm 35 toward the terminal 5, and then wedging the lead 21 in one or the other of clips 20. The arm 35 tends to spring downward under the bias of the stressed spring 33, which flexes as illustrated in Fig. 1 to force together or contract the convolutions on the side of its axis toward the insulator and to force apart the convolutions on the side of its axis away from the insulator, and this holds the link under tension between the heads 71 and 73. When the fusible element 79 of the link blows, the arm 35 springs down and pulls the lead 43 out of the fuse tube 23 to extinguish the arc that may result from the blowing of the element 79.

It will be understood that the spring 33 may be coiled so that, in its unstressed condition, its axially displaced convolutions are either in engagement or spaced apart, these types of helical springs being well-known.

An important advantage of securing the spring 33 to the insulator in the position illustrated and described is that spring action of the arm 35 is assured, when the fuse link blows, even under severe icing conditions, without any necessity for

providing an ice shield or the like. Another advantage of the invention resides in the provision of the loop 37 for the bolt connector 67, whereby a conductor may be attached directly to the loop and a continuous current path is provided from the connector through the loop, the spring 33 and the arm 35 to the outer free end of the arm 35.

In view of the above, it will be seen that the several objects of the invention are achieved and other advantageous results attained.

As many changes could be made in the above constructions without departing from the scope of the invention, it is intended that all matter contained in the above description or shown in the accompanying drawing shall be interpreted as illustrative and not in a limiting sense.

I claim:

1. A fuse switch comprising an insulator, a terminal mounted on said insulator adapted for attachment of one lead of a fuse link, an electrically conductive resilient rod having a portion thereof coiled about an axis into a helically convoluted spring, the convolutions of which are axially displaced, and another portion thereof forming a cantilever arm extending outward from one end of the spring, the spring being secured at its other end to the insulator spaced from said terminal with the arm extending outward away from the insulator, said arm being adapted for attachment of the other lead of the fuse link to its free end when its free end is forced against the bias of the spring toward the terminal to hold the fuse link under tension between the terminal and the free end of the arm, the spring being secured to the insulator with its axis generally in the plane in which the arm moves when its free end is forced toward the terminal, so that when the free end of the arm is forced toward the terminal, the convolutions of the spring are forced together on one side of the spring axis and forced apart on the other.

2. A fuse switch comprising an insulator, a terminal mounted on said insulator adapted for attachment of one lead of a fuse link, an electrically conductive resilient rod having a portion thereof coiled about an axis into a helically convoluted spring, the convolutions of which are axially displaced, another portion thereof forming a cantilever arm extending outward from one end of the spring in a direction generally transverse to the direction of length of the spring, and another portion forming a loop extending outward from the other end of the spring, the spring being secured at its said other end to the insulator spaced from said terminal with the arm extending outward away from the insulator, said arm being adapted for attachment of the other lead of the fuse link to its free end when its free end is forced against the bias of the spring toward the terminal to hold the fuse link under tension between the terminal and the free end of the arm, the spring being secured to the insulator in such position that when the free end of the arm is forced toward the terminal, the convolutions of the spring are forced together on one side of the spring axis and forced apart on the other.

3. A fuse switch comprising an elongate insulator, a terminal extending transversely outward from one end of said insulator having a clip at its outer end for attachment of one lead of a fuse link, an electrically conductive resilient rod having a portion thereof coiled about an axis into a helically convoluted spring, the convolutions of which are axially displaced, and another portion thereof forming a cantilever arm extending out-

ward from one end of the spring in a direction generally transverse to the direction of length of the spring, the spring being secured at its other end to the other end of the insulator with the arm extending generally transversely outward away from the insulator generally in the plane of the insulator and the terminal, said arm having a clip at its free end for attachment of the other lead of the fuse link when its free end is forced against the bias of the spring toward the terminal to hold the fuse link under tension between the terminal and the free end of the arm, the spring being secured to the insulator in such position that when the free end of the arm is displaced toward the terminal, the convolutions of the spring are forced together on one side of the spring axis and forced apart on the other.

4. A fuse switch comprising an elongate insulator, a terminal extending transversely outward from one end of the insulator on one side of the insulator and having a clip at its outer end for attachment of one lead of a fuse link, a bracket extending transversely outward from the other end of the insulator on said one side of the insulator, an electrically conductive resilient rod having a portion thereof coiled about an axis into a helically convoluted spring, the convolutions of which are axially displaced, and another portion thereof forming a cantilever arm extending outward from one end of the spring generally transverse to the direction of length of the spring, the spring having its other end secured to the bracket with its axis generally parallel to the length of the insulator and with the arm extending transversely outward away from the insulator on said one side of the insulator, said arm having a clip at its free end for attachment of the other lead of the fuse link when the free end of the arm is forced toward the terminal.

5. A fuse switch comprising an elongate insulator, a terminal extending transversely outward from one end of the insulator on one side of the insulator and having a clip at its outer end for attachment of one lead of a fuse link, a bracket extending transversely outward from the other end of the insulator on said one side of the insulator, an electrically conductive resilient rod having a portion thereof coiled about an axis into

a helically convoluted spring, the convolutions of which are axially displaced, another portion thereof forming a cantilever arm extending outward from one end of the spring generally transverse to the direction of length of the spring, and another portion forming a loop extending outward from the other end of the spring generally parallel to the axis of the spring, the spring having its other end secured to the bracket with its axis generally parallel to the length of the insulator and with the arm extending transversely outward away from the insulator on said one side of the insulator, said arm having a clip at its free end for attachment of the other lead of the fuse link when the free end of the arm is forced toward the terminal.

6. A fuse switch comprising an elongate insulator, a terminal extending transversely outward from one end of the insulator on one side of the insulator and having a clip at its outer end for attachment of one lead of a fuse link, a bracket extending transversely outward from the other end of the insulator on said one side of the insulator, an electrically conductive resilient rod having a portion thereof coiled about an axis into a helically convoluted spring, the convolutions of which are axially displaced, another portion thereof forming a cantilever arm extending outward from one end of the spring generally transverse to the direction of length of the spring, and another portion forming a loop extending outward from the other end of the spring generally parallel to the axis of the spring, the spring having its other end secured to the bracket and extending from the bracket toward the terminal with its axis generally parallel to the length of the insulator and with the arm extending transversely outward away from the insulator on said one side of the insulator, said arm having a clip at its free end for attachment of the other lead of the fuse link when the free end of the arm is forced toward the terminal, the loop extending in the opposite direction from the bracket and carrying a connector for attaching a conductor thereto.
